[57] **CLAIM**

The ornamental design for a combined telephone and clock radio, as shown and described.

DESCRIPTION

FIG. 1 is a front, top and right side perspective view of a combined telephone and clock radio showing my new design;

FIG. 2 is a right side elevational view thereof;

FIG. 3 is a top plan view thereof with the telephone handset removed;

FIG. 4 is a bottom plan view thereof;

FIG. 5 is a front elevational view thereof;

FIG. 6 is a rear elevational view thereof;

FIG. 7 is a left side elevational view of the telephone handset alone;

FIG. 8 is a front elevational view thereof;

FIG. 9 is a rear elevational view thereof;

FIG. 10 is a top plan view thereof; and

FIG. 11 is a bottom plan view thereof.

Fig.8.
